TOY TRAIN AND TRACK

Milton S. Dunkelberger, Dayton, Ohio

Application April 10, 1947, Serial No. 740,573

2 Claims. (Cl. 46—216)

1

This invention relates to a toy train and more particularly to a toy train of the type using a manually operated tiltable track and a gravity operated train.

One object of this invention is to provide a toy train which may be manufactured and sold at a low cost and yet is durable and fascinating to operate.

More specifically, it is an object of this invention to provide a gravity operated train or the like in which the center of gravity is low enough not to cause the train to leave the track when negotiating curves.

A further object of this invention is to provide an improved supporting arrangement for a manually movable track having both straight sections and curved sections for guiding a gravity operated train.

Further objects and advantages of the present invention reside in the construction and combination of parts and in the mode of operation as will be apparent from the following description, reference being had to the accompanying drawings wherein a preferred form of the present invention is clearly shown.

In the drawings:

Figure 1 is a perspective view of a preferred form of my invention;

Figure 2 is an elevational view showing the locomotive coupled to the tender;

Figure 3 is an elevational view showing the passenger coach;

Figure 4 is a similar view showing the caboose;

Figure 5 is a plan view of the link and pin coupler arranged between the tender and the locomotive;

Figure 6 is a bottom view, partly in section, showing the construction of the passenger coach;

Figure 7 is a fragmentary elevational view showing the hook coupler on the front end of the engine in a raised position in which position the coupler is prevented from coupling when pushing another car;

Figure 8 is a fragmentary elevational view showing the coupler on the front end of the engine coupled to a car;

Figure 9 is a side elevational view of one of the wheels;

Figure 10 is a front elevational view showing the construction of one of the wheels;

Figure 11 is a fragmentary side elevational view showing one form of mounting for the table on which the train track is mounted;

Figure 12 is a view similar to Figure 11 showing a modified arrangement for mounting the table; and,

2

Figure 13 is a fragmentary perspective view showing the construction of the track.

Referring now to the drawings wherein I have shown a preferred embodiment of my invention, reference numeral 20 designates a tiltable table or platform on which a one piece train track 22 is mounted. The track 22 is preferably made from flat sheet metal stock which has been bent to form a U-shaped channel as best illustrated in Figure 13. Perforations 24 are provided along the length of the track 22 for the reception of the rivets or the like for fastening the track to table 20. The entire upper surface of the table 20 may be provided with scenic decorations of various types as no train operating mechanism is necessary. For purpose of illustration, I have shown a river 26, a roadway 28 and a lake 30. As shown in Figure 11, the underside of the table 20 is preferably provided with a spherical element 32 arranged substantially centrally thereof for supporting the table on a socketed supporting element or base 34 which is adapted to rest on the floor or any other surface on which the device is to be operated. The height of the support 34 is chosen so that it will allow the necessary amount of tilting of the table to successfully operate the train but prevent tilting the table to such an angle that the train can be caused to operate at a speed great enough to cause the momentum of the train to upset the train at the curves.

In Figure 12 of the drawing, I have shown a slightly modified arrangement for tiltably supporting the table 20. While the arrangement shown in Figure 12 has some disadvantage over the arrangement shown in Figure 11, it does have the advantage that the supporting post 36 will not be lost since it is attached to the table 20 by some suitable means such as the screw 38.

The train comprises a plurality of units or playing pieces such as an engine 40, a tender 42, a passenger coach 44 and a caboose 46. The tender is removably coupled to the engine 40 by means of a link and pin coupler 50. The link is pivotally connected to the tender 42 by suitable means such as the rivet 52. The forward end of the link 50 is provided with a pin 54 which projects through the link 50 and extends into the apertured element 56 provided adjacent the rear end of the engine 40 as best shown in Figure 2. The front end of the engine 40, the rear end of the tender 42, and the rear end of the coach 44 are each provided with a hook coupler 60 which is pivotally mounted and is adapted to be operated by means of a pivoted uncoupler 62. The one end of the passenger coach and both ends of the

caboose are provided with a loop coupler 64 (see Figures 6 and 8) which is adapted to cooperate with the hook couplers provided on adjacent units of the train. The loop couplers 64 each have their projecting ends bent at an angle as best illustrated at 66 in Figure 8 so as to cam the hook couplers upwardly when two units of the train are to be coupled together.

When any one of the hook couplers 60 is raised to a position corresponding to the position in which the hook coupler 60 is shown in Figure 7, the center of gravity of the hook is such that the hook will remain in the raised position. By virtue of this construction, it is possible to render any one of the hook couplers inoperative at will. However, the hook coupler may be caused to fall of its own accord if the car on which the hook coupler is located is struck a sharp enough blow by one of the other cars. Thus, when the hook coupler 60 on the engine is in its raised position, it is possible to have the engine 40 move up to the caboose and push the caboose without becoming coupled to the caboose but it is also possible to operate the engine at such a speed relative to the caboose as to cause the impact between the engine and the caboose to jar the hook coupler out of its raised position with the result that the engine will become engaged to the loop coupler on the caboose before the caboose moves completely away from the engine. By use of skill, it is apparent that very interesting effects can be obtained by using the above described coupling element construction. This is especially true in view of the fact that the units of the train are all gravitationally operated whereby it takes special skill to control the relative speed of the various units of the train.

Each unit of the train is preferably constructed entirely of light weight moulded material or sheet material except for the wheels 70 and the axles 72 which are made of heavy material such as brass, iron, or the like, so as to cause the center of gravity of each unit to be close to the track. By virtue of this construction the train can travel at a fairly high speed around the curves without danger of upsetting.

A very interesting effect is obtained by making the table rectangular in shape. The rectangular shape of the table not only makes it possible to use both straight and curved track sections but also makes it possible to more conveniently regulate the speed of the train.

The tendency of any train is to slow up around curves and to travel much faster over the straight sections of the track, assuming a constant propelling force, but with the construction disclosed herein, the propelling force is less when the train is on the straight section than when the train is on the curved section at the end of the table. This is due to the fact that when the one end of the rectangular table is in contact with the floor or other supporting surface the angle formed

between the table and the supporting surface is smaller than the angle formed between the table and the supporting surface when the side of the table touches the supporting surface.

While the form of embodiment of the invention as herein disclosed, constitutes a preferred form, it is to be understood that other forms might be adopted, all coming within the scope of the claims which follow.

- 10 Having thus described my invention, I claim:
1. In a manually actuated amusement device of the class described, a table, means for tiltably supporting the table for gyratory movement in response to manual tilting, continuous track means on said table having both straight portions and curved portions, a plurality of cars supported for rolling movement on said track means, and a coupler element carried by each end of each car, certain of said coupler elements comprising a loop coupler and other of said coupler elements comprising a complementary gravity actuated pivoted hook coupler, the center of gravity of each hook coupler being arranged to move past the pivot point thereof so as to cause said hook coupler to be gravitationally held either in loop engaging position or out of loop engaging position.
  2. In an amusement device of the class described, a table, a post secured to the bottom side of said table for tiltably supporting the table for gyratory movement, track means on said table having both straight portions and curved portions, a plurality of cars, and a coupler element carried by each end of each car, certain of said coupler elements comprising a loop coupler and other of said coupler elements comprising a complementary gravity actuated pivoted hook coupler, the center of gravity of said hook coupler being arranged to move past the pivot point thereof so as to cause said hook coupler to be gravitationally held either in loop engaging position or out of loop engaging position, said track means comprising a one-piece sheet metal track element substantially U-shaped in cross section whereby the upper ends of the U form spaced rails for guiding said cars, each of said cars comprising a relatively light weight molded plastic body provided with relatively heavy wheels for supporting said body on said track means.

MILTON S. DUNKELBERGER.
